DRILL STEEL GUIDE

Charles F. Osgood, Claremont, N. H., assignor to
 Sullivan Machinery Company, a corporation of
 Massachusetts

Application February 17, 1942, Serial No. 431,250

13 Claims. (Cl. 255—51)

This invention relates to rock drills, and more particularly to improvements in a drill steel guide especially designed for use with a mounted rock drill of the drifter type.

In mounted rock drills of the drifter type, the drill hammer motor is slidably guided in the guideways of a guide shell, and there is usually provided some sort of drill steel guide or centralizer at the forward end of the guide shell for centering the drill steel actuated by the hammer motor during starting or "spotting" of a drill hole. In such drill steel guides or centralizers, the guide is oftentimes automatically released from guiding relation with the drill steel as the drill hammer motor is fed forwardly along the shell guideways, and various devices have been devised to effect such automatic release. Also in such guides or centralizers a pair of pivoted guide arms are frequently employed to embrace the body of the drill steel; and these guide arms, when they are automatically swung outwardly into non-guiding position as the hammer motor approaches the guide, project laterally a substantial distance beyond the sides of the guide shell in order to clear the hammer motor to enable the latter to move forwardly beyond the guide. Such lateral projection of the guide arms beyond the sides of the guide shell is found to be undesirable, particularly in the restricted quarters in an underground mine. In other types of guiding or centralizing devices which did not employ pivoted guide arms, while lateral compactness was obtained the desired guiding of the drill steel was lacking.

An object of the present invention is to provide an improved drill steel guide or centralizer which, to a large extent, overcomes the disadvantages of certain previous devices. Another object is to provide an improved drill steel guide having novel mounting means for the guiding elements thereof whereby the latter when released from guiding relation with the drill steel, are maintained within the lateral limits of the guide shell. Still another object is to provide an improved drill steel guide embodying a pair of cooperating guide arms which are pivotally mounted to swing about rectangularly related axes into and out of guiding relation with the drill steel. A further object is to provide an improved drill steel guide embodying releasable locking means for holding the guide arms in guiding relation with the drill steel, and which is automatically released upon engagement thereof by the drill hammer motor as the latter is fed forwardly along the shell guideways. Yet another object is to provide a

novel drill steel guide having improved locking means for holding the guide in guiding relation with the drill steel, and which is automatically released upon engagement thereof by the drill hammer motor as the latter is fed forwardly along the shell guideways. Yet another object is to provide a novel drill steel guide having improved locking means for holding the guide in guiding relation with the drill steel and novel means for automatically moving the guide into non-guiding position when the locking means is released. A still further object is to provide an improved drill steel guide embodying a novel spring arrangement for automatically moving the guide arms into their non-guiding position when released from their guiding relation with the drill steel. Yet another object is to provide an improved drill steel guide having a novel arrangement and combination of parts. Other and further objects and their resultant advantages will be apparent after the invention becomes better understood from an examination of the specification and claims, in connection with the accompanying drawings, in which several embodiments of the invention are illustrated.

In the drawings:

Fig. 1 is a fragmentary side elevational view of a rock drill with which an illustrative embodiment of the improved drill steel guide is associated.

Fig. 2 is a front elevational view of the rock drill and steel guide shown in Fig. 1, with parts shown in vertical section.

Fig. 3 is a front end elevational view of the rock drill and steel guide shown in Figs. 1 and 2, showing the guide arms in their laterally released position.

Fig. 4 is a view similar to Fig. 1, with parts shown in vertical section, with the guide in its non-guiding position.

Fig. 18 is a front end elevational view of the rock drill and steel guide shown in Fig. 16 with the guide arms in their laterally released position.

Fig. 19 is a view similar to Fig. 16, showing the guide in its non-guiding position.

Fig. 20 is a cross sectional view taken substantially on line 20—20 of Fig. 16.

Fig. 21 is a horizontal sectional view taken substantially on line 21—21 of Fig. 16.

In the several embodiments of the invention, the improved drill steel guide is shown associated with a conventional hammer rock drill of the drifter type. It will be evident, however, that the improved drill steel guide may be associated with other types of drills, if desired.

The hammer rock drill disclosed herein in the several embodiments of the invention comprises a conventional drill hammer motor 1, slidably guided on a conventional guide shell 2, the latter adapted to be mounted on a conventional drill support. The drill hammer motor comprises a motor cylinder 3 containing a reciprocating hammer piston (not shown), for percussively actuating a drill steel 4, the latter being supported in a usual chuck within a front chuck housing 5, suitably attached to the front end of the motor cylinder. The hammer motor cylinder has usual lateral guides 6, 6 slidably received within longitudinal guideways 1, 1 of the guide shell. The hammer motor may be fed along the shell guideways in any conventional manner. Since the rock drill disclosed is of a conventional design and is well known to those skilled in the art, further description and illustration thereof are herein unnecessary.

In the embodiment of the invention shown in Figs. 1 to 8, inclusive, the improved drill steel guide or centralizer, generally designated 8, comprises a bracket 9 attached by bolts 10, which herein may be the usual shell side bolts, to the front end of the guide shell. This bracket has a forwardly located lug 11 provided with a transverse bore 12 through which a pivot bolt 13 passes. Pivotedly mounted on the projecting ends of the pivot bolt 13 are arm supports 14, 14 on which are pivotally mounted on parallel pivot bolts 15 a pair of guide arms 16, 16. The axes of the pivot bolts 15, 15 are arranged at right angles to the axis of the pivot bolt 13, so that the guide arms may swing into and out of their guiding relation with the drill steel about rectangularly related pivotal axes. These guide arms have guiding portions 17 appropriately shaped to engage the body of the drill steel to hold the latter centered during starting or "spotting" of a hole, in the manner well known to those skilled in the art. The guide arms have projecting lugs 18, 18 near their pivots, and these lugs are engageable at 19 with

the outer sides of the arm supports 14 for limiting lateral swinging movement of the guide arms about the pivot bolts 15. The arm supports 14 have depending lugs 20 engageable at 21 with the bottom of the bracket 9 for limiting downward swinging of the arm supports and guide arms about the pivot bolt 13. Arranged within suitable recesses formed in the opposite sides of the bracket lug 11 and surrounding the pivot bolt 13 are coiled torsion springs 22, while surrounding the pivot bolts 15 are coiled torsion springs 23, and these torsion springs 22, 23 act automatically to swing the guide arms about the rectangularly related pivotal axes into their non-guiding position. The torsion springs 23 serve to swing the guide arms a slight distance apart sufficient to clear the sides of the drill steel body while the torsion springs 22 act to swing the arm supports 14 to move the guide arms forwardly and downwardly out of the path of movement of the drill hammer motor. Pivotedly mounted on a transverse pivot pin 24 on the upper side of the bracket 9 is a spring-pressed latch 25 having an appropriately shaped locking portion 26 engageable with lugs 27 integral with the guide arms 16, 16 for locking the guide arms in guiding relation with the drill steel. This latch has an upper cam surface 28 adapted to be engaged by the forward end of the chuck housing 5 of the drill hammer motor as the latter is fed forwardly along the shell guideways, so that the latch is depressed to effect release of the guide prior to engagement of the hammer motor with the guide arms. When this latch is released from the arm lugs 27, the torsion springs 23 automatically swing the guide arms about their parallel pivots into their laterally released position as shown in Fig. 3, and thereafter the torsion springs 22 automatically swing the guide arms forwardly and downwardly about the transverse pivot into their non-guiding position shown in Fig. 4. When the guide arms are in the position shown in Fig. 4, they are disposed out of the path of movement of the hammer motor, so that the latter may be fed forwardly along the shell guideways past the guide.

In the operation of this embodiment of the improved drill steel guide, when it is desired to start or "spot" a drill hole the guide arms 16, 16 may be swung upwardly about the transverse pivot bolt 13 into the position shown in Fig. 1, and thereafter swung inwardly about the pivot bolts 15 into guiding relation with the drill steel as shown in Fig. 2. As the guide arms are swung into guiding relation with the drill steel, the latch 25 snaps over the locking lugs 27 on the guide arms to lock the latter in position. As the drill hammer motor is fed forwardly along the shell guideways, the guide arms serve to center the drill steel, and when the front chuck housing 5 engages the cam surface 28 on the latch the latter is depressed to effect release of the locking lug 26 from the lugs 27 on the guide arms. When the latch is in its released position and the guide arms are unlocked, the torsion springs 23 act automatically to swing the guide arms apart into their laterally released position shown in Fig. 3, sufficiently to clear the sides of the steel body, and thereafter the torsion springs 22 act to swing the arm supports 14 about the transverse pivot to move the guide arms into the non-guiding position shown in Fig. 4, out of the path of movement of the drill hammer motor. As the guide arms swing apart laterally, the lugs 18 thereon move into engagement with the outer surfaces of the arm supports, thereby to limit

outward swinging movement of the arms; and as the arm supports swing downwardly, downward movement of the guide arms is limited by engagement of the support lugs 20 with the bottom of the bracket 9. By the provision of separate and distinct pivotal mountings for the guide arms, the latter may be individually placed in guiding relation with the drill steel, for instance, during "spotting" of a drill hole on an inclined face when but a single arm suffices to prevent lateral deflection of the drill steel.

In the embodiment of the invention shown in Figs. 9 to 15, inclusive, a bracket 30, attached to the front end of the guide shell 2, has forwardly projecting, laterally spaced lugs 31, 31 provided with aligned openings through which a transverse pivot bolt 32 passes. A pair of guide arms 33, 33 have their hubs 34 arranged between the bracket lugs in the manner shown in Fig. 13, and are pivotally mounted on the pivot bolt 32 to swing both laterally and downwardly about rectangularly related pivotal axes. The bores 35 in the arm hubs have relatively inclined widened portions 36, 37 which permit lateral tilting or rocking of the arm hubs with respect to the pivot bolt while providing adequate bearing surfaces for the downward pivotal movement of the arms about the pivot bolt. Coaxial with the pivot bolt and arranged within suitable recesses 38 in the bracket lugs are coiled torsion springs 39 which constantly urge the guide arms forwardly and downwardly about the pivot bolt axis. The arm hubs have depending bosses 40 formed with bores 41 in which spring-pressed plungers 42 are arranged. These plungers engage the surfaces of arcuate bearing portions 43 integral with the bracket lugs, as shown in Fig. 15. These plungers constantly tend to rock the guide arms toward their laterally released position shown in Fig. 11, and cooperate with the bracket lugs in limiting downward swinging movement of the arms. Pivoted on a transverse pivot pin 44 on the upper part of the bracket is a spring-pressed latch 45 having an appropriately shaped locking lug 46 engageable with lugs 47, 47 integral with the guide arms. This latch holds the guide arms in their guiding position shown in Fig. 10, and is formed with a cam surface 48 adapted to be engaged by the forward end of the chuck housing 5 as the hammer motor is fed forwardly along the shell guideways. When the latch is released from the arm lugs 47, the spring-pressed plungers 42 automatically swing the guide arms apart into their laterally released position, and thereafter the torsion springs 39 act automatically to swing the guide arms forwardly and downwardly about the pivot bolt 32 into their non-guiding position shown in Fig. 12, out of the path of movement of the hammer motor.

The mode of operation of this embodiment of the invention is similar to that above described. When the hammer motor is fed forwardly along the shell guideways, the front chuck housing 5 engages the cam surface 48 on the latch depressing the latter and releasing the locking lug 46 from the locking lugs 47 on the guide arms. When the latch is in released position, the spring-pressed plungers 42 throw the guide arms apart into their laterally released position shown in Fig. 11, so that guiding portions thereof just clear the sides of the body of the drill steel. The torsion springs 39 then act automatically to swing the guide arms forwardly and downwardly about the pivot bolt 32 into their non-guiding

position shown in Fig. 12, out of the path of movement of the hammer motor. Likewise, as in the other form of the invention above described, by the provision of the separate arm mountings, the guide arms may be placed either separately or simultaneously in guiding relation with the drill steel.

In the embodiment of the invention shown in Figs. 16 to 21, inclusive, a bracket 50, attached to the front end of the guide shell 2, has laterally spaced, forwardly located lugs 51, 51 provided with aligned openings through which a transverse pivot bolt 52 passes. Pivotally mounted on this pivot bolt between the bracket lugs is an arm support 53 which carries parallel pivot bolts 54, 54 on which a pair of cooperating guide arms 55, 55 are pivotally mounted. The axes of the pivot bolts 54 are arranged at right angles to the axis of the transverse pivot bolt 52, so that the guide arms swing into and out of guiding relation with the drill steel about rectangularly related pivotal axes. Arranged within suitable recesses 56 in the opposite sides of the arm support 53 and surrounding the pivot bolt 52 are coiled torsion springs 57, 57 which constantly urge the arm support, together with the guide arms, forwardly and downwardly about the axis of the pivot bolt 52. Suitable means is provided for urging the guide arms constantly apart, i. e. towards their laterally released position, and for normally maintaining them with their guiding portions just clearing the sides of the drill steel body. For this lateral urging, I have shown a spring arrangement disclosed in a copending application of one J. C. Curtis, Serial No. 447,016, filed June 15, 1942, said arrangement including a torsion spring 58 with coiled portions 59 surrounding the pivot bolts. The guide arms have lugs 60 near their pivots, and these lugs are engageable with the outer sides of the arm support 53 for limiting lateral swinging movement of the guide arms, and the arm support 53 has a lug 61 engageable with the bottom of the bracket for limiting downward swinging movement of the guide arms. The guide arms have at their inner sides integral lugs 62 and 63, and the former lug has a longitudinal bore 64 in which a locking bolt 65 is slidably guided. This locking bolt has an appropriately shaped locking lug 66 engageable with a projection 67 on the lug 63 for holding the arms together in guiding relation with the drill steel. A coil spring 68 urges the locking bolt rearwardly into its locking position. Also integral with the rear sides of the guide arms are lugs 69 engageable with projections 70 integral with the bracket for holding the guide arms, when the latter are in guiding relation with the drill steel, from swinging forwardly and downwardly about the axis of the pivot bolt 52.

As in the embodiments of the invention above described, when the drill hammer motor is fed forwardly along the shell guideways, the chuck housing 5 engages the locking bolt 65 shoving the latter forwardly against the action of the spring 68 to release the locking lug 66 from the arm projection 67. When the locking bolt is in its released position, the torsion spring 58 automatically swings the arms apart into their laterally released position shown in Fig. 18, and as the arms swing apart the lugs 69 thereon are released from the bracket projections 70. When the guide arms are released from locking engagement with the bracket, the torsion springs 57 act automatically to swing the guide arms forwardly

and downwardly about the pivot bolt 52 into their non-guiding position shown in Fig. 19 out of the path of movement of the drill hammer motor. In this embodiment of the invention, it is not possible to place separately the guide arms in guiding relation with the drill steel, since the particular construction of the locking bolt and torsion springs precludes this.

In the several embodiments of the invention above described, it is the intention initially to effect swinging of the arms apart about the arm pivot axes into their laterally released position, so that the guiding portions thereof just clear the sides of the body of the drill steel, and thereafter to swing the arms forwardly and downwardly about the right angle axis into their non-guiding position. By thus first swinging the arms a slight distance apart the guiding portion of the arms will clear the steel before the arms start to swing downwardly. By moving the arms apart only a distance sufficient to clear the sides of the drill steel body, undesirable lateral projection of the guide arms beyond the sides of the guide shell is eliminated. In the embodiment of the invention last described, the guide arms are positively locked against downward swinging movement by the arm locking lugs engaging projections on the bracket, and in the first and second embodiments similar positive locking means may be employed. For instance, in the second embodiment above described, the arm hubs and bracket lugs may have suitable inter-engaging locking portions which are released as the arms rock apart. Also, the torsion springs may be so designed as to assure swinging of the arms apart prior to the forward and downward swinging movement of the arms.

As a result of this invention it will be noted that an improved drill steel guide or centralizer is provided which is extremely rugged and compact in construction and simple in design. It will further be evident that by the provision of the improved pivotal mounting for the guide arms, enabling the latter to swing about rectangularly related pivotal axes in the manner disclosed, excessive lateral projection of the guide arms beyond the sides of the guide shell is eliminated. Furthermore, by the provision of the particular arm locking arrangement and the spring means for automatically moving the arms into their non-guiding position, jamming of the parts by inadvertent engagement of the drill hammer motor with the guide is prevented, and the guide is quickly thrown into non-guiding position just as soon as the lock is released irrespective of the supported position of the drill. Other uses and advantages of the invention will be clearly apparent to those skilled in the art.

While there are in this application specifically described several embodiments which the invention may assume in practice, it will be understood that these embodiments of the same are shown for purposes of illustration and that the invention may be further modified and embodied in various other forms without departing from its spirit or the scope of the appended claims.

What I claim as new and desire to secure by Letters Patent is:

1. In a drill steel guide, a pair of cooperating, relatively movable guide elements adapted to engage a drill steel, and means for pivotally mounting said guide elements both for swinging movement about rectangularly related axes, said axes, when the guide is in guiding position, lying in

parallel planes extending in parallelism with the drill steel.

2. In a drill steel guide, a pair of cooperating, relatively movable guide elements adapted to engage a drill steel, and means for pivotally mounting said guide elements both for swinging movement about rectangularly related axes, certain of said pivotal axes being disposed parallel to the longitudinal axis of the drill steel when said guide

elements are in steel guiding position whereby said guide elements may initially swing outwardly relative to each other away from the drill steel, and the remainder of said rectangularly related axes disposed at right angles to said parallel axes, whereby said guide elements may swing downwardly into an out-of-the-way non-guiding position.

3. In a drill steel guide, a pair of cooperating pivoted guide arms adapted to engage a drill

steel, said arms being relatively swingable about parallel axes, said parallel axes, when the guide is in guiding position, lying in a plane extending in parallelism with the drill steel, and a support swingable about a transverse axis at right angles to said arm pivot axes, said arms being pivotally mounted on said pivoted support and swingable with the latter about said transverse axis.

4. In a drill steel guide, a pair of cooperating, relatively movable guide elements movable into

positions in and out of guiding relation with a drill steel, and mounting means for said guide elements, said mounting means including means for supporting said guide elements for movement in a plurality of directions whereby said guide elements are initially movable on said mounting means a slight distance apart out of steel guiding relation in transverse planes perpendicular to the longitudinal axis of the drill steel sufficiently to clear the sides of the drill steel and thereafter movable on said mounting means forwardly and downwardly in planes in parallelism with the drill steel into their non-guiding position.

5. In a drill steel guide, a pair of cooperating, relatively movable guide elements movable into positions in and out of guiding relation with a drill steel, and pivotal mounting means for said guide elements, said pivotal mounting means including means for supporting said guide elements

for swinging movement, when in steel guiding relation, about axes parallel to the longitudinal axis of the drill steel, and for swinging movement also about a right angle axis whereby said guide elements are initially swingable on said mounting means relative to each other out of steel guiding relation about axes parallel to the longitudinal axis of the drill steel a slight distance apart sufficient to clear the sides of the drill steel and thereafter swingable on said mounting means about an axis disposed at right angles to said pivotal axes forwardly and downwardly into their non-guiding position.

6. In a rock drill, a guide along which a drill

steel actuator is guided for movement, a bracket on the forward end of said guide, a pair of cooperating guide arms movable relative to each other into positions in and out of guiding relation with a drill steel, means for pivotally mounting said guide arms on said bracket to swing relative thereto about rectangularly related axes, and releasable means on said bracket for locking said guide arms in their steel guiding position, said locking means being releasable to free said arms for movement out of guiding relation with the drill steel, said drill steel actuator as it moves

forwardly along said guide being engageable with an element of said locking means for effecting release thereof, said guide arms being first swingable about certain of said axes a slight distance apart sufficient to clear the drill steel and thereafter swingable about a right angle axis in a forward and downward direction into their non-guiding position out of the path of said drill steel actuator.

7. In a drill steel guide, a pair of cooperating, relatively movable guide arms movable into positions in and out of guiding relation with a drill steel, and separate pivotal mountings for said guide arms each providing rectangularly related pivotal axes, said arms being swingable independently about said rectangularly related axes into and out of guiding relation with the drill steel.

8. In a drill steel guide, guiding means including a guide element movable into positions in and out of guiding relation with a drill steel, and mounting means for said guiding means including means for pivotally mounting said guide element to swing from its guiding position in one direction about an axis disposed parallel to the longitudinal axis of the drill steel and in a different direction about a right angle axis.

9. In a drill steel guide, a pair of guiding elements movable relative to each other into positions in and out of guiding relation with a drill steel, and means for mounting said guiding elements each for swinging movement in different directions at right angles relative to each other one of which is in transverse planes perpendicular to the longitudinal axis of the drill steel, said guiding elements being movable first in one direction and thereafter in a right angle direction.

10. In a drill steel guide, a guiding element movable into positions in and out of guiding relation with a drill steel, and means for mounting said guiding element for swinging movement into aforesaid positions, said mounting means including means for supporting said guiding element for swinging in one direction from its guiding position in transverse planes perpendicular

5 to the longitudinal axis of the steel and means for supporting said guiding element for swinging in another direction in longitudinal planes parallel to the longitudinal axis of the steel.

11. In a drill steel guide, a support, a pair of guide arms adapted to engage a drill steel and mounted on said support for independent swinging movement toward and from the drill steel about parallel axes arranged at the opposite sides of said support, and a lock on said support and movable into and out of locking relation with said arms for holding said arms in guiding relation with the steel, said lock being engageable with said arms independently whereby said arms may be individually or simultaneously locked in guiding position.

10 12. In a drill steel guide, a support, a pair of guide arms adapted to engage a drill steel and mounted on said support for independent swinging movement toward and from the drill steel about parallel axes arranged at the opposite sides of said support, a lock on said support and movable into and out of locking relation with said arms for holding said arms in guiding relation with the steel, said lock being engageable with said arms independently whereby said arms may be individually or simultaneously locked in guiding position, and means for automatically throwing said guide arms apart into their laterally released position when said lock is in released position.

20 13. In a drill steel guide, a pair of cooperating pivoted guide arms adapted to engage a drill steel, and a pair of supports, said arms being mounted one on each of said supports for swinging movement relative thereto on axes which are parallel, when the guide is in guiding position, to the axis of the drill steel, and said supports each swingable about an axis in a single 25 straight line which extends transversely with respect to said parallel axes and makes a right angle with a line parallel to the axis of the drill steel.

30 40 CHARLES F. OSGOOD.
